FUEL PUMP

Glenn J. Williams, Morristown, Tenn.

Application May 18, 1938, Serial No. 208,653

2 Claims. (Cl. 221—95)

My invention relates to improvements in fuel pumps and more particularly to that type equipped with mechanism for denoting the quantity and indicating the price of liquid dispensed therefrom.

One of the principal objects of my invention is to provide means incorporated within a fuel pump for resetting the calculating mechanism which denotes the quantity and/or indicates the price of the liquid dispensed from the pump.

Another object of my invention is to provide a device of the above described character wherein the resetting means is operable for operating the switch mechanism for controlling the operation of the pump.

A further object of my invention is to provide a device of the above described character which is simple in construction, efficient in operation, durable in use and economical in manufacture.

Other objects and advantages will be apparent from the following description, appended claims and annexed drawings.

Referring to the drawings wherein like reference characters designate like parts throughout the several views:

Figure 1 is a front elevation of a fuel pump illustrating my invention incorporated therein.

Figure 2 is a sectional view taken on the line 2—2 of Figure 1.

Figure 3 is a view similar to Figure 1 showing the parts in another position.

Figures 4 and 5 are sectional views taken on the lines 4—4 and 5—5 of Figure 3 respectively.

In practicing my invention I employ a fuel pump 5 of typical construction and which is ordinarily used in dispensing gasoline or the like for use in motor vehicles. A typical form of said pump as illustrated in the drawings comprises a housing 6 having secured to the bottom thereof an electric motor 7 connected to a pump 8 by means of a pulley and belt assembly 9. Said pump is connected to a fuel intake line 10 and to a fuel discharge line 11. Said fuel discharge line 11 has interposed therein a drive mechanism of ordinary construction housed within a casing 12. The drive mechanism is connected by means of a shaft 13 to a calculating mechanism provided with indicia wheels 14 having indicia thereon visible through windows 15 in a housing 16. Said calculating mechanism functions to denote the quantity and the price of gasoline dispensed through a hose connection 17 connected to the outer end of the line 11, the same being of ordinary construction.

The calculating mechanism is also provided

with the usual shaft 18 for resetting the indicia wheels after a predetermined amount of the fuel has been dispensed from the pump. The outer end of the shaft 18 has fixed thereto a gear 19 in mesh with a gear 20 fixed on a shaft 21 on which is mounted a ratchet gear 22 for a purpose hereinafter described.

My reset mechanism, in the preferred embodiment illustrated in the drawings, comprises a bracket 25 secured to the bottom of the housing 6 and on the upper end of which is pivoted a substantial horizontally extending arm 26, one end of said arm being connected to and under the influence of a coil spring 27 connected to the bottom of the housing 6. A stop member 28 is secured to one of the walls of the housing and serves to limit the downward movement of the end of the arm 26 to which the spring 27 is connected. The opposite end of the arm 26 has journaled therein a crank arm 29, one end of which is fixed to a disk 30 and the opposite end pivoted to the lower end of a connecting rod 31. The upper end of the connecting rod 31 is pivotally connected to a yoke arm 32, one end of which is pivoted to the housing as at 33 and the opposite or free end 33a adapted to normally overlie and engage the upper face of a bumper 34, preferably constructed of rubber, mounted on the upper end of a support 35 secured to the bottom of the housing.

Interposed between the bottom of the housing and the calculating mechanism is a horizontally extending shelf 36 on which is mounted a motor switch 37 equipped with a switch arm 38 having pivoted thereto the lower end of a connecting rod 39 for operating said switch and thereby effecting operation of the motor 7 through an electrical circuit (not shown). Operation of said motor serves to operate the pump 8 through the medium of the pulley and belt assembly 9 heretofore described.

One side of the housing 6 is provided with a bearing 40 in which is journaled a shaft 41 extending into the housing and the outer end of said shaft is equipped with a handle 42 for a purpose hereinafter set forth. Pinned on the inner end of the shaft 41 and movable therewith is an arm 43, one end of which is connected to the upper end of the rod 39 and the opposite end connected by means of a link 44 to a bell crank lever 45 pivoted to the housing 6. Subjacent the bell crank lever 45 there is provided a sliding bolt 46 having an inclined face 47 and fashioned with a projection 48 for engagement with the lower end of the bell crank lever 45 and said bolt is slid-

ably carried in guides 49 secured to the housing.

A coil spring 50 embraces said bolt, one end of which engages one of the guides 49 and the other end the projection 48 to normally urge said bolt in a direction away from the rod 39.

The housing 6 is also provided with a pair of laterally extending spaced guide members 51 through which is slidably mounted a vertically extending bar 52 having an upper pivoted section 53.

Above and adjacent the lower guide member 51 said bar is fashioned with a projection 54 having an inclined face for engagement with the inclined face 47 of the bolt 46. Below said lower guide member 51 the bar is equipped with a coil spring 55, the upper end of which engages the lower guide member 51 and the lower end a collar 56 secured on the lower end of the bar 52. The spring 55 serves to normally urge the bar towards the bottom of the housing 6 and the lower end of the bar into engagement with the free end 33a of the yoke arm 32 when the pump is in operative position as hereinafter set forth.

The upper end of the section 53 of the bar 52 has pivoted thereto an arm 57 rotatably mounted on the shaft 21. Said arm 57 has pivotally mounted thereon a gravity actuated dog 58, said dog being adjustable relative to said arm by means of an adjusting screw 59 mounted in the upper end of the section 53 as clearly illustrated in Figures 2 and 3 of the drawings. The arm 57 is equipped with a stop in 60 for limiting the movement of the dog when the arm 57 is in raised position as illustrated in Figure 3.

Mounted on the inner end of the shaft 41 adjacent the arm 43 is a disk 61 formed with a cam section 62 and which provides a locking face 63 for engagement with one end of a lever 64 pivoted to the housing 6 as at 65. The opposite end of said lever is adapted for actuating engagement with a laterally extending section 66 of a vertically extending arm 67, the lower end of which is secured to the bar 52.

Mounted on the shaft of the motor 7 is a disk 68 for frictional engagement with the peripheral face of the disk 30 for effecting initial operation of the reset mechanism.

In operation, the parts being in the position illustrated in Figure 2, the handle 42 is manually operated to impart counterclockwise movement to the shaft 41. Upon rotation of the shaft 41 the arm 43 will be operated to actuate the switch 37 thereby starting the motor 7 and pump 8. Upon starting of the motor the disk 68 rotates causing disk 30 in turn to rotate and thereby raise the yoke arm 32 through the medium of the crank arm 29 and connecting rod 31. Raising of the yoke arm 32 effects a raising of the bar 52 and positions the dog 58 in engagement with the ratchet gear 22 as illustrated in Figure 3. As the bar 52 is raised the projection 54 thereon engages the inclined face 47 of the latch bolt 46 to permit the projection 54 to seat upon the upper face of the latch bolt 46 as illustrated in Figure 3. During the upward movement of the bar 52 the laterally extending section 66 is likewise moved upwardly to permit the lever to be pivoted and rest upon the peripheral face of the disk 61, the face 63 being disposed under said lever. In this position of the parts the free end 33a of the yoke arm 32 rests upon the upper face of the bumper 35, said bumper being in extended position due to the release of the pressure of the bar 52 therefrom. In this position the yoke arm is disposed

in such a manner that the disk 30 is disengaged from the disk 68 and maintained therefrom by the tension exerted by the spring 27.

From the foregoing it will be apparent that when the parts are in the position as above described gasoline or other fuel may be dispensed through the hose connection 17 and the amount dispensed together with the price thereof is indicated by the indicia on the indicia wheels 14 in the usual manner. Upon a predetermined amount of fuel being dispensed the same is cut off at the hose connection through the nozzle mechanism carried thereby in the usual manner and said nozzle mechanism placed in non-operating position on the support carried by the housing. In this position the indicia wheels 14 still indicate the quantity and price of the fuel dispensed and the motor and pump are still in operation, the fuel being by-passed to the fuel reservoir in the usual manner. To reset the calculating mechanism and actuate the switch 37 for stopping the motor and pump, the handle 42 is moved to impart rotation to the shaft 41 in a clockwise direction and thereby rotate the disk to permit the end of the lever to seat against the face 33. This movement of the shaft 41 also actuates the arm 43 in a manner to move the switch arm 37 to break the electrical connection in the circuit to the motor and at the same time actuate the bell crank lever 45 through the medium of the link 44 to move the latch bolt 46 towards the rod 39 and release the projection 54. Release of the projection 54 from the upper face of the latch bolt 46 causes the bar 52 to be projected downwardly by the action of the spring 55 thereby positioning the end of the bar 52 in engagement with the free end 33a of the yoke arm 32 and effecting compression of the bumper 34 and engagement of the disk 30 with the disk 62.

The downward movement of the bar 52 also imparts movement to the arm 57 pivoted thereto and which in turn effects rotation of the gear 22 through the medium of the dog 58. Rotation of the gear 22 likewise rotates gear 19 through the medium of the shaft 21 and gear 20 and thereby resets the calculating mechanism through the medium of the shaft 18. The ratio of the gear 20 relative to the gear 19 is such as to cause the shaft 18 to be actuated in a manner to position the indicia wheels 14 slightly past reset position. However, said calculating mechanism is equipped with a spring (not shown) which in turn reverses the movement of the shaft 18 and positions the indicia wheels in reset position. When the bar 52 has been projected downward by the spring 55, the laterally extending section 62 of the arm 57 engages the end of the lever 64 and maintains the opposite end thereof out of engagement with the face 63 to permit rotation of the shaft 44 to effect another pumping operation as heretofore described.

What I claim is:

1. The combination of a fuel dispensing pump assembly of that class provided with a housing in which is located a calculating mechanism for indicating the quantity of fuel dispensed, a pump for dispensing said fuel, an electric motor equipped with an armature shaft for operating the pump, a switch operable for controlling the electric circuit to said motor, and a reset shaft for resetting said calculating mechanism; and of a reset device comprising a bar slidably mounted in said housing and provided with a pivoted end section, a drive shaft mounted in said housing and geared to said reset shaft, a ratchet gear 75

mounted on said drive shaft for operating the latter and said reset shaft, a connecting member pivoted to said drive shaft and said section whereby to maintain said section spaced from 5
5 said gear, a gravity actuated dog pivoted on said member for operating said gear to reset said calculating mechanism, a manually operable shaft extending into said housing, an arm mounted on said last mentioned shaft and connected to said 10
10 switch, a bell crank mounted in said housing and connected to said last mentioned arm, a spring pressed latch bolt operable by said bell crank for releasing said bar to actuate said reset shaft, and a drive mechanism connected to said armature 15
15 shaft and engageable by said bar whereby said bar is actuated to a position for operating said reset shaft upon movement of said manually operable shaft to operate said switch.
2. The combination of a fuel dispensing pump assembly of that class provided with a housing in which is located a calculating mechanism for indicating the quantity of fuel dispensed, a pump for dispensing said fuel, an electric motor equipped with an armature shaft for operating 20
20 the pump, a switch operable for controlling the electric circuit to said motor, and a reset shaft for resetting said calculating mechanism; and of a reset device comprising a bar slidably mounted
25
25 in said housing and provided with a pivoted end section, a drive shaft mounted in said housing and geared to said reset shaft, a ratchet gear mounted on said drive shaft for operating the latter and said reset shaft, a connecting member pivoted to said drive shaft and said section whereby to maintain said section spaced from said gear, a gravity actuated dog pivoted on said member for operating said gear to reset said calculating mechanism, a manually operable shaft extending into said housing, an arm mounted on said last mentioned shaft and connected to said switch, a bell crank mounted in said housing and connected to said last mentioned arm, a spring pressed latch bolt operable by said bell crank for releasing said bar to actuate said reset shaft, a drive mechanism connected to said armature shaft and engageable by said bar whereby said bar is actuated to a position for operating said reset shaft upon movement of said manually operable shaft to operate said switch, a locking lever pivotally mounted in said housing and actuated by said bar, and a cam fixed on said manually operable shaft and engageable by said lever to preclude actuation of said switch to close said circuit to said motor in advance of the actuation of said reset shaft by said bar.

GLENN J. WILLIAMS.
